WINDOW CONSTRUCTION

Judie Brent, St. Louis, Mo.

Application July 15, 1936, Serial No. 90,776

2 Claims. (Cl. 20—49)

This invention relates to window constructions and the object of the invention is to provide a window construction where the sash or sashes, as the case may be, are mounted for sliding movement as well as swinging movement vertically, the arrangement being such that the window glass may be swung inwardly to facilitate washing both sides of the glass, and also to increase ventilation.

10 Further in accordance with the present invention the window glass may be supported at the desired angle to provide for ventilation without draft.

The invention together with its objects and 15 advantages will be best understood from a study of the following description taken in connection with the accompanying drawings, wherein:—

Figure 1 is an elevational view of a window construction embodying the features of the present invention and as viewed from the outer side 20 of the window.

Figure 2 is a view similar to Figure 1 but viewing the window from the inner side thereof and with the weight boxes removed.

25 Figure 3 is a longitudinal sectional view through the window illustrating in broken lines various positions of the sashes.

Figure 4 is a horizontal sectional view taken substantially on the line 4—4 of Figure 1.

30 Figure 5 is a perspective view of a portion of a sash.

Figure 6 is a detail sectional view showing the manner of pivotally mounting a sash with a guide strip.

35 Figure 7 is a perspective view of a guide strip.

Figure 8 is a perspective view of a panel guide strip.

Figure 9 is a detail sectional view taken substantially on the line 9—9 of Figure 2.

40 Referring to the drawings by reference numerals, it will be seen that in the preferred embodiment thereof the window structure comprises a suitable frame 5 adapted to accommodate, in the present instance, an upper sash 6 and a lower sash 7.

The sides 8 of the frame in the upper ends thereof are provided with suitable openings in which are journaled pulleys 9 over which are trained sash cords 10 for the sashes 6 and 7 and 50 which sash cords are equipped with the usual sash weights 11 which are of course concealed in sash boxes (not illustrated).

Each sash 6, 7 comprises a suitable frame 12 having a window pane 13 mounted therein in a 55 more or less conventional manner, the manner of

mounting and securing the pane 13 within its frame 12 not being of the essence of the present invention.

Also for each of the sashes 6, 7 there is secured to each of the sides 8 of frame 5 a guide strip 14 of metal or other suitable material, the strip being secured by screws or any other suitable fastening means as is apparent.

Each strip 14 has its longitudinal edge portions bent outwardly from the plane of the strip 10 at obtuse angles to the plane of the strip to provide flanges 15.

For cooperation with each strip 14 each sash frame 12 is provided on its respective opposite side with guide strips 16 complementary to the 15 guide strips 14.

Each guide strip 16 is formed of metal or other suitable material and is channel-shaped in cross section, with the sides 17 of the panel having longitudinal free edge portions bent inwardly to 20 provide flanges 18 which engage behind the flanges 15 of a complementary guide strip 14 in a manner clearly shown in Figure 9.

For securing each sash frame 12 to its guide strip 16 for pivotal swinging movement in a vertical plane relative to the strip each frame 12 at the lower opposite corners thereof, and as clearly shown in Figure 6, has secured thereto through the medium of screw or similar fastening elements 19 substantially L-shaped plates 20 the 30 vertical flanges of which are provided with pivot studs 21 which are engaged in openings provided therefor in the lower ends of the strip 16 and are then upset as clearly shown in Figure 6 to provide for a pivotal connection between the sash 35 frame 12 and its associated guide strips 16.

Also each sash 12 has suitably mounted in the opposite side members thereof spring projected latch bolts 22 provided with actuating knobs 23 that project from the frame so as to easily be 40 grasped for retracting the bolts 22.

Also the guide strips 16 adjacent their upper ends are provided with keeper slots 24 with which the bolts 22 are engageable as shown in Figure 9 for securing the frame 12 engaged with the strips 45 16 so that said frame and strips may be slid vertically as a unit for positioning the selected window sash at the desired open position.

To confine the swinging movement of each sash 12 to an inward direction, the strips 16 have 50 secured to the outer sides thereof elongated plates 25 that have free longitudinal edge portions provided with flanges or projections 26 which engage in longitudinal grooves provided therefor in the adjacent side rails of the as- 55

sociated sash frame 12 as will be clear from a study of Figures 4, 5, 8, and 9. Thus it will be seen that the strips 25 act as stops which will permit the sash frames 12 to be swung only in an inward direction.

From the foregoing it will be seen that the structure will admit of the raising and lowering of the sashes 6 and 7, and, with the latch bolts released, of the swinging of the frames of the 10 sashes vertically into a full horizontal position as suggested in broken lines in Figure 3, or with respect to the upper sash 6 the swinging of the frame of the upper sash 6 to a position of angular adjustment as suggested by broken lines in 15 the upper portion of Figure 3 whereby ventilation without draft may be obtained. In this connection it will be understood that the vertical adjustment of the upper sash 6 with respect to the lower sash 7 will determine the angular position 20 to which the sash frame 12 of the upper sash 6 may be swung for obtaining such ventilation without draft.

It will also be appreciated that such a structure will admit of the swinging of the sash frames 25 inwardly of the room to a position as will facilitate the washing of both sides of the window glass of either upper or lower sash.

If desired, and as shown in Figure 7, instead of directly nailing or otherwise securing the strips 30 14 to the window frame there may be interposed between each strip 14 and the side 8 of the window frame 5 an oblong plate 28 of metal or other suitable material as suggested in Figure 7.

It is thought that a clear understanding of

the construction, utility and advantages of an invention of this character will be had without a more detailed description.

Having thus described the invention, what is claimed as new is:—

1. In a window construction, a frame having a vertical fixed stile, a guide track secured vertically to the stile and having its longitudinal edges bent to form flanges directed obliquely from the stile, a window sash including a framing rail opposed to said track, a runner channel-shaped in cross-section and opposed to said track between the track and sash rail, the side walls of the channel having their free ends directed laterally into converging relation and having interlocking and tracking contact with said track flanges, said sash being pivoted to said runner, a stop plate secured to one side wall of the channel and overlying the sash rail, the free edge of said stop plate being formed into a key flange 10 and said sash rail having a groove forming a keyway for reception of said key flange. 15

2. In a sash construction, a frame, a substantially L-shaped plate secured to one corner of the 20 frame, the vertical portion thereof being provided with an attaching and pivoting stud, an auxiliary rail to which said stud is pivoted, said rail constituting a sliding runner for the sash and being channel-shaped in cross-section with the side walls turned laterally to provide 25 guiding and retention flanges, said sash having a latch, the web portion of said channel being apertured to provide a keeper for the latch. 30
